UNITED STATES PATENT OFFICE

166,531

BRACELET OR SIMILAR ARTICLE

Israel Daniels, Flushing, N. Y.

Application December 23, 1949, Serial No. 6,803

Term of patent 3½ years

(Cl. D45—4)

To all whom it may concern:

Be it known that Israel Daniels, a citizen of the United States of America and resident of Flushing, Queens County, New York, has invented a new, original, and ornamental Design for a Bracelet or Similar Article, of which the following is a specification, reference being had to the accompanying drawing, forming part thereof, in which,

Fig. 1 is a top plan view of a bracelet embodying my new design;

Fig. 2 is a bottom plan view thereof;

Figs. 3 and 4 are top and bottom plan views, respectively, illustrating the links in an extended position; and

Fig. 5 is an edge elevation of the bracelet.

The dominant feature of my design resides in the plane surfaced top links, which links are characterized by the relatively long, slanting center portion in association with the short, equal-sized offset jogs at each end of said center portion.

I claim:

The ornamental design for a bracelet or similar article, substantially as shown and described.

ISRAEL DANIELS.
